(57) **CLAIM**

The ornamental design for a lamp, as shown and described.

DESCRIPTION

FIG. 1 is a perspective view of a first embodiment of a lamp design;

FIG. 2 is front elevation thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a perspective view of a second embodiment of a lamp design;
FIG. 9 is front elevation thereof;
FIG. 10 is a rear elevation view thereof;
FIG. 11 is a right elevation view thereof;
FIG. 12 is a left, elevation view thereof;
FIG. 13 is a top plan view thereof;
FIG. 14 is a bottom plan view thereof;
FIG. 15 is a perspective view of a third embodiment of a lamp design;
FIG. 16 is front elevation thereof;
FIG. 17 is a rear elevation view thereof;
FIG. 18 is a right elevation view thereof;
FIG. 19 is a left elevation view thereof;
FIG. 20 is a top plan view thereof; and
FIG. 21 is a bottom plan view thereof;
FIG. 22 is a perspective view of a fourth embodiment of a lamp design;
FIG. 23 is a bottom plan view thereof;
FIG. 24 is a perspective view of a fifth embodiment of a lamp design;
FIG. 25 is a bottom plan view thereof;
FIG. 26 is a perspective view of a sixth embodiment of a lamp design; and
FIG. 27 is a bottom plan view thereof;
FIG. 28 is a perspective view of a seventh embodiment of a lamp design; and,
FIG. 29 is a bottom plan view thereof.
The oblique shade lines in the figures show reflectivity, transparency, or translucency. The dash-dash broken lines in the figures illustrate portions of the lamp which form no part of the claimed design. The dot-dash broken lines in the figures define the bounds of the claimed design and form no part thereof.
